(57) **CLAIM**

The ornamental design for a remote control box for ships, as shown and described.

DESCRIPTION

FIG. 1 is a front right perspective view of a remote control box for ships showing my new design;

FIG. 2 is a rear left side elevational view thereof;

FIG. 3 is a right side view thereof;

FIG. 4 is a left side view thereof;

FIG. 5 is a front view thereof;

FIG. 6 is a rear view thereof; and,

FIG. 7 is a top view thereof.

The bottom is plain and forms no part of the design.
